UNITED STATES PATENT OFFICE.

CORNELIS F. M. VAN BERKEL, OF LAPORTE, INDIANA, ASSIGNOR TO U. S. SLICING MACHINE COMPANY, OF LAPORTE, INDIANA, A CORPORATION OF INDIANA.

CLAMP FOR SLICING-MACHINES.

1,315,751.

Specification of Letters Patent.

Patented Sept. 9, 1919.

Application filed August 15, 1917. Serial No. 186,403.

To all whom it may concern:

Be it known that I, CORNELIS F. M. VAN BERKEL, a subject of the Queen of the Netherlands, residing at Laporte, in the county 5 of Laporte and State of Indiana, have invented certain new and useful Improvements in Clamps for Slicing-Machines, of which the following is a specification.

This invention relates to a device for holding 10 material while it is being cut by a slicing machine, and has for its object the provision of an article of the character named which shall be of improved construction and more efficient and convenient in operation than 15 devices of this character previously known.

The invention is exemplified in the combination and arrangement of the parts shown in the accompanying drawing and described in the following specification, and it is more 20 particularly pointed out in the appended claims.

In the drawing—

Figure 1 is a front elevation of a clamp embodying one form of the present invention.

Fig. 2 is an elevational view looking from the right in Fig. 1.

Fig. 3 is a top plan view of the mechanism shown in Figs. 1 and 2; and

Fig. 4 is a vertical section showing details of construction.

In slicing machines of the character commonly in use the material to be sliced is clamped upon a plate or support which is mounted to slide upon a reciprocating table. Such a table is represented at 1 in the drawing, and the sliding plate or support is shown at 2. The plate 2 may be provided with a pair of upright posts or standards 3 and 4, upon which is mounted the clamp for the material shown at 5. The clamp proper consists of two bars 6 and 7 which have their ends pivoted together by a bolt 8 which passes through openings in pins 9 and 10 swiveled 35 in the ends of the bars 6 and 7 respectively. The end of the bar 6, opposite the bolt 8, is mounted on a pivot bolt 11, carried by a clutch collar 12 which surrounds the standard 4. The clutch collar 12 is provided 40 with an off-set arm 13 overlying the upper surface of the clamping bar 6 so that when the bar 6 is tilted to a predetermined angle about the pivot 11, it will engage a set screw 14 in the end of the arm 13 and release the 45 clamping action of the collar 12 upon the

post 4. When the bar 6 is pressed firmly into engagement with the material 5, the collar 12 grips the post 4 and holds the bar against upward movement. The pin 10 has a limited swiveling movement in the end of the 50 bar 7, so that when the bar 7 is raised the clamping bar 6 will be held at such an angle to the horizontal that the clutch collar 12 will be maintained in alignment with the post 4 so that it will slide freely, in either 55 direction along the post 4. The mechanism thus far described is shown and claimed in Patent No. 1,175,025 to W. A. van Berkell, upon which patent this invention is an improvement, but it should be understood that 60 the novel features of this invention are applicable to other forms of clamping devices than that shown in the patent referred to.

The end of the clamping bar 7 which slides upon the upright 3 is provided with an 65 elongated bearing 15 which slides upon the post 3, and is of sufficient length to prevent binding between the bearing and the post. Above the bearing 15 is a chamber 16, in which is mounted a clutch plate 17 having 70 an opening therethrough which loosely surrounds the post 3 in a manner to grip the post when the plate is tilted obliquely. The plate 17 rests upon a fulcrum ridge 18 projecting upwardly from the floor of the chamber 16, and the end of the plate on the opposite side of the post from the fulcrum 75 18 is provided with a coil spring 19 which normally tilts the plate into position to grip the post 3 to hold the bar 7 against upward 80 movement. The chamber 16 is provided with a removable cover plate 20, which carries a lug or shoulder 21 in position to engage the end of the plate 17 when the plate is in position to permit free movement of the bar 7 85 along the post 3.

A second clutch plate 22 surrounds the post 3 above the chamber 16 and is provided with an elongated bearing surface 23 at one side thereof. This elongated bearing surface 100 prevents tilting of the plate into position to grip the post 3 in such a way as to hold the plate against downward movement along the post, but permits gripping of the post by the plate to hold the plate against upward movement. A projection 24 extends from one side of the clutch plate 22 between the legs of a loop bar 26 to hold the clutch plate from rotation about the post 3.

A lever 28 is carried by a pivot 29 sup-

ported above the end of the clamping bar 7 and is provided with an extension 30 arranged to engage the lower surface of the projection 24 when the lever 28 is moved 5 downwardly, as shown in Fig. 4. A second projection 31 is carried by the lever 28 in position to engage the upper surface of the clamping plate 17 when the lever is tilted upwardly, as shown in Fig. 2. When this 10 last occurs the clamping plate 17 is tilted about the fulcrum ridge 18 until the end of the plate engages the shoulder 21, thus bringing the opening in the plate into alinement with the post 3, so that the bar 7 will slide 15 freely upon the post.

To place a piece of meat, or other material, into the machine to be sliced, the operator grasps the handle 28 and lifts upwardly thereon. This movement causes the projection 20 31 to engage the clutch plate 17 and move this plate into position to slide freely along the post 3. At the same time the clutch plate 22 is freed from the projection 30 and falls into position to rest upon the 25 upper surface of the cover for the chamber 16. This leaves the bar 7 free to slide upon the post 3, and the upward pull of the operator upon the lever 28 will raise the clamp to any desired height. The upward movement 30 of the bar 7 tilts the clamping bar 6 into position to release the clutch loop 12 so that it also slides freely upon the post 4. While the clamp is in its upper position the material 5 may be inserted beneath the 35 clamping bar 6 without difficulty since there is no post upon the plate 2 at the corner of the plate adjacent the pivot bolt 8. After the material has been inserted in place, the clamp may be lowered bodily until the lower 40 surface of the bar 6 contacts with the upper portion of the material 5. When this occurs further lowering of the clamp will cause the bar 6 to tilt about the material 5 as a fulcrum, forcing the pivot 11 upwardly and 45 thus causing the clutch loop 12 to grip the post 4 to resist upward movement. Further downward pressure causes the bar 6 to clamp the material upon the supporting plate 2. This clamping pressure is 50 greatly increased by the operation of the lever 28. When the bar 7 has moved downward as far as it will go by gravity, the operator presses downwardly upon the lever 28 which causes the projection 30 to engage 55 the under surface of the clutch plate 22, which in turn grips the post 3 and forms a fixed bearing for the projection 30. Downward pressure upon the handle 28 is transmitted to the pivot pin 29, and thus the 60 power exerted upon the clamp 17 is greatly multiplied. As the lever 28 moves downwardly about the pin 29, the clutch plate 17 is released and automatically grips the post 3 because of the action of the spring 19 and 65 holds the bar 7 against any return upward

movement. It is thus seen that all the operator need do is to lift upward on the handle 28 when he wishes to raise the clamp, and to press downwardly upon the handle when he wishes to force the clamp into engagement with the material to be held. The downward pressure is greatly multiplied by the lever 28 so that the material may be firmly clamped in position without a straining effort on the part of the operator, who 75 need use but one hand to operate the clamp.

I claim:

1. In combination, a support for material to be sliced, a clamping bar for holding material on said support, means for guiding 80 said clamping bar to move bodily toward and from said support through successive parallel positions, and power multiplying mechanism arranged to impart a swinging movement to said clamping bar for forcing said clamping bar into contact with said material.

2. In combination, a support for material to be sliced, a clamping bar for holding material on said support, a guide on which said bar is slidably mounted and along which it moves bodily toward said support, and a power multiplying device arranged to impart a swinging movement to said clamping bar for forcing said bar into engagement 95 with material on said support.

3. In combination, a support for material to be sliced, a clamping bar for holding material on said support, a guide along which said bar is slidably mounted, a clutch for 100 holding said bar in adjusted positions along said guide, and a lever for moving said bar along said guide and arranged to increase the force exerted by the operator for moving said bar.

4. In combination, a clamping bar, a guide for said bar, and a pair of clutch devices connected with said bar and arranged to engage said guide to control the movement of said bar along said guide, both of said clutch 110 devices being arranged to oppose movement of said clamping bar in the same direction along said guide.

5. In combination, a clamping bar, a guide for said bar, a pair of clutch devices 115 for controlling the movement of said bar along said guide, and a lever for operating said clutch devices, one of said clutch devices being arranged to form an abutment against which said lever bears to move said 120 clamping bar.

6. In combination, a clamp for material to be sliced, a guide for said clamp, a clutch adjustably mounted on said guide, and a lever arranged to bear upon said clutch as 125 a stop to move said clamp along said guide.

7. In combination, a clamp for material to be sliced, a guide for said clamp, a pair of clutches for controlling the movement of said clamp relative to said guide, and a lever 130

for controlling said clutches and for moving said clamp along said guide.

8. In combination, a clamp for material to be sliced, a guide for said clamp, a lever for moving said clamp along said guide, and a clutch adjustable along said guide to form a fulcrum for said lever to enable said lever to move said clamp relative to said guide.
9. In combination, a clamp for material to be sliced, a guide for said clamp, a lever for moving said clamp along said guide, a clutch adjustable along said guide and arranged to form a fulcrum for said lever, and a second clutch for holding said clamp in its adjusted positions.

10. In combination, a clamp for material to be sliced, a guide for said clamp, a pair of clutch devices for controlling the movement of said clamp along said guide, and a lever for operating said clutch devices and arranged in one position to free said devices to permit movement of said clamp relative to said guide and in another position to bear upon one of said clutches as a fulcrum for moving said clamp and to leave the other of said clutches free to hold said clamp against return movement.

11. In combination, a clamp for material to be sliced, a guide for said clamp, a lever for moving said clamp along said guide, and clutching mechanism for controlling the movement of said clamp upon said guide and arranged to coöperate with said lever to permit free movement of said clamp along said guide when said lever is moved in one direction and to enable said lever to form a power multiplying device for moving said clamp in another direction.

12. In combination, a clamp for material to be sliced, a guide for said clamp, a lever pivotally mounted on said clamp, and a pair of clutch devices for controlling the movement of said clamp along said guide and arranged to permit free movement of said clamp when said lever is drawn in one direction and to form a fulcrum for said lever to force said clamp in the opposite direction and also to prevent return movement of said clamp when so forced.

13. In combination, a clamping bar having an opening at one end thereof, a guide passing through said opening, a lever pivoted to said bar, a pair of clutch plates surrounding said guide, and projections on said lever for controlling said clutch plates, said projections arranged to position said clutch plates for free movement along said bar

when said lever is moved in one direction and to bear against one of said clutch plates to force said clamping bar along said guide 60 when said lever is moved in the opposite direction and to simultaneously free the other of said clutch plates to hold said bar against return movement.

14. In combination, a clamp for material to be sliced, a guide for said clamp, a lever for moving said clamp along said guide, means for engaging said guide to afford a fulcrum for said lever and separate means for engaging said guide to hold said clamp 70 in adjusted positions.

15. In combination, a support for material to be sliced, a clamping bar for holding material on said support, said bar being adjustable bodily relative to said support 75 for bringing said bar into engagement with material to be held thereon, and a power multiplying device for imparting a supplemental movement to said bar to press said bar forcibly into engagement with said material and positively acting means for holding said bar in the position into which it is thus moved.

16. In combination, a support for material to be sliced, a clamping bar for holding 85 material on said support, a pivotal connection between said support and one end of said bar, a guide for said pivoted connection along which said connection slides freely when the end of said clamping bar opposite 90 said connection is moved upwardly, said pivotal connection being adjustable toward and from said support, and a power multiplying device for swinging said bar about said pivotal connection to press said bar into engagement with material on said support.

17. In combination a support for material to be sliced, a smooth upright guide on said support, a pivot mounted for sliding movement along said guide, a clamping bar 100 having one end thereof carried by said pivot, means for moving said clamping bar and pivot bodily toward said support to bring said clamping bar into engagement with material on said support, and a power multiplying device to impart a supplemental movement of said bar about said pivot to force said bar into engagement with said material.

In testimony whereof I have signed my 110 name to this specification, on this 13th day of August, A. D. 1917.

CORNELIS F. M. VAN BERKEL.
